CLAIM

The ornamental design for a cover for a child safety seat, as shown and described.

DESCRIPTION

FIG. 1 is a perspective view of the cover for a child's safety seat showing my new design.

FIG. 2 is a front view thereof.

FIG. 3 is a bottom view thereof.

FIG. 4 is a left side view thereof.

FIG. 5 is a top view thereof.

FIG. 6 is a left side view thereof, with the center flap open.

FIG. 7 is a perspective view of the left side and top thereof, with the hood in a closed position; and,

FIG. 8 is a perspective view showing the left side and rear thereof, with the hood in a closed position.

The broken line showing of the child safety seat is for illustrative purposes only and forms no part of the claimed design.
